RAY VAN SANDT, OF BAKERSFIELD, AND WILLIAM T. WILLIAMS, OF TAFT, CALIFORNIA, ASSIGNEES OF SIXTY PER CENT. TO WILLIAM C. RAE, OF PASADENA, CALIFORNIA.

INSULATED ELECTRODE.

1,390,819.

Specification of Letters Patent. Patented Sept. 13, 1921.

Application filed December 29, 1919. Serial No. 347,886.

To all whom it may concern:

Be it known that we, RAY VAN SANDT and WILLIAM T. WILLIAMS, both citizens of the United States, residing at Bakersfield and 5 Taft, California, respectively, have invented a new and useful Insulated Electrode, of which the following is a specification.

This invention relates to insulated electrodes particularly adapted for use in high 10 voltage electric circuits and especially adapted for installation in tanks for use in oil treating systems.

The object of the invention is to provide an improved insulated electrode which will 15 simultaneously withstand temperatures of wide differences at different points and which will not rupture under expansion and contraction due to these temperatures.

A further object is to provide an electrode 20 supported within a hollow insulating casing and separated from said casing by successive concentric layers of different insulating materials all embedded in and bound together as a unitary structure by an insulating cement or wax.

Another object relates to the method of 25 constructing an insulated electrode of the above type which consists of supporting the electrode within a hollow insulating casing 30 and closing the bottom open end of the casing, placing tubes of insulating material concentrically and telescopically around the electrode, filling all the intermediate spaces with molten cement or wax, closing the top 35 open end of the casing with suitable plug or cap with the electrode exteriorly extended and attached thereto.

Various other objects and advantages will 40 be more fully apparent from the following description of the accompanying drawings which illustrate a preferred form of embodiment of the invention and which form a part of this disclosure.

Of the drawings:

45 Figure 1 is a vertical transverse section of our improved insulated electrode.

Fig. 2 is a plan section on line x^2-x^2 , Fig. 1.

Fig. 3 is a vertical transverse section 50 through a tank of an oil treating system having installed therein our improved insulated electrode.

In the drawings 1 designates a tank having a head 2 provided with a medial orifice

and 3 designates a pipe screw-threaded into 55 said orifice and forming a central chamber into which the insulated electrode extends. An inlet pipe 4 extends through the side wall of the tank and is screw-threaded into the side wall of the pipe 3, the pipe 4 being 60 welded to the tank to form a tight joint. An outlet pipe 5 is screw-threaded in and welded to the wall of the tank.

This particular installation is only illustrative of one of the many uses for which 65 the electrode of the present invention is adapted.

The casing 6 of the electrode is of tubular form and is made of insulating material, preferably of bone fiber, or of other fiber of 70 a like character which is of a yielding nature as compared to hard brittle materials. Screw-threaded or otherwise attached to the casing is a supporting collar 7 also of insulating material and attached to the tank by 75 bolts 8 extending through orifices in said collar and screw-threaded in the tank head, a lead gasket 9 being inserted between the collar and tank to form a tight joint.

The electrode as an integral unit 80 comprises the electrode rod 10 attached to and extending downwardly from a supporting plug 11 screw-threaded in the bottom end of the casing bore, and a terminal rod 12 also secured to said plug and extending upwardly 85 centrally through the bore of the casing. Seated upon the plug 11 and surrounding the rod 12 is a bushing 13 preferably formed of mica or other like material and having a laterally extending flange 14. An insulating tube 15 also formed of mica is longitudinally inserted in the bore of the casing 90 loosely over the rod 12 and rests on the bushing 13. A glass tube 16 is next inserted in the bore of the casing loosely over the mica 95 insulating tube and resting on the flange 14 of the mica bushing 13.

With the parts assembled as thus far explained, molten insulating wax, preferably 100 of the character usually used in sealing various forms of electrical equipment is poured into the casing bore. This way 21 fills the space between the bore of the casing and the glass tube, the space between the glass tube and the mica tube and also the space between the mica tube and the terminal rod 12 105 of the electrode. While the wax is still in the molten state a mica bushing 17 is pressed

into the upper end of the glass tube with its flange 18 resting upon the top edge surface of said tube.

A metal plug 19 is then screwed into the upper end of the bore in the casing as a closure for said bore, with the terminal rod 12 of the electrode extending through a central bore therein and attached thereto by soldering or otherwise to form a tight seal.

10 A lead wire 20 connects in the usual manner with the terminal rod, as shown.

This structure provides an insulated electrode which is of a nature which will withstand the stress incident to the transmission of high tension current and to expansion and contraction of the component elements due to temperature variations.

Another particular advantage resides in the simplicity of construction, convenience 20 of assembling and replacement of parts, and cheapness of manufacture.

While well adapted to fulfill the objects primarily stated, the particular construction here shown and described is of course susceptible of modification and the invention is not necessarily to be considered as limited 25 in this regard.

We claim:

1. An insulated electrode comprising an 30 insulating casing having a longitudinal bore, and an electrode centrally supported within said bore and incased in concentric layers of different insulating materials.

2. An insulated electrode comprising an 35 insulating casing having a longitudinal bore, an electrode centrally supported within said bore, and a plurality of concentric layers of insulating material and intermediate layers of insulating wax between the electrode and 40 the walls of the bore.

3. An insulated electrode comprising an 45 insulating casing having a longitudinal bore, an electrode centrally supported within said bore, a mica tube surrounding the electrode, a glass tube surrounding the mica tube, and insulating wax binding the tubes and elec-

trode together and the glass tube to the walls of the bore.

4. An insulated electrode comprising an insulating casing having a longitudinal bore, 50 a plug secured in one end of said bore, an electrode attached to said plug and centrally positioned within the bore, concentric tubes of insulating material telescopically positioned around the electrode, insulating wax binding the tubes and electrode together and the outer tube to the walls of said bore, and a closure for the opposite end of the bore contacting with the electrode.

5. An insulated electrode comprising an 60 insulating casing having a longitudinal bore, a plug screw-threaded into one end of said bore, an electrode projecting outwardly from the plug, a terminal rod attached to the plug and centrally positioned within said bore, a mica tube surrounding the rod, a glass tube surrounding the mica tube, and a closure for the opposite end of the casing bore.

6. An insulating electrode comprising an 70 insulating casing having a longitudinal bore, a plug screw-threaded into the bottom end of said bore, an electrode supported by the plug and centrally positioned within the casing bore, a mica bushing seated on the plug 75 and surrounding the electrode, a mica tube surrounding the electrode and seating on said bushing, a glass tube surrounding the mica tube and seating on the bushing, insulating wax maintaining the elements within the casing bore against movement, a second mica bushing surrounding the electrode and engaging the tops of the tubes, and a closure for the casing bore contacting with the electrode.

Signed at Los Angeles, California, this 85
20th day of December, 1919.

RAY VAN SANDT.

WILLIAM T. WILLIAMS.
